(57) **CLAIM**

The ornamental design for a laundry basket, as shown and described.

DESCRIPTION

FIG. 1 is a top perspective view of a laundry basket, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1.

The broken lines in the drawings illustrate the portions of the laundry basket, which form no part of the claimed design. The dash broken lines encircling the enlarged views indicate cutoff boundaries for the enlarged detailed portion views and form no part thereof.
